Primary Examiner—Prabhakar G. Deshmukh**[57]****CLAIM**

The ornamental design for a wide wire basket with mounting pins, as shown and described.

DESCRIPTION

FIG. 1 is a perspective view of a wide wire basket with mounting pins showing my new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a right side elevational view thereof; the left side elevational view being a mirror image thereof. The broken line showing of support is for illustrative purpose only and forms no part of the claim.
